FRANKLIN RANSOM, OF BUFFALO, NEW YORK.

Letters Patent No. 77,214, dated April 28, 1868.

IMPROVEMENT IN HYDRAULIC ENGINES.

The Schedule referred to in these Letters Patent and making part of the same.

TO ALL WHOM IT MAY CONCERN:

Be it known that I, FRANKLIN RANSOM, of the city of Buffalo, in the county of Erie, and State of New York, have invented a certain new and improved Hydraulic Engine; and I do hereby declare that the following is a full and exact description thereof, reference being had to the accompanying drawings, making part of this specification, which represents a longitudinal vertical section of my improved machine.

The object of my invention is the construction of a machine, to be operated by the pressure produced by the elevation of the fountain or supply above the locality of the machine, by which a portion of said water may be forced to a greater or less height above that of the fountain. The machine is especially designed for elevating water to the upper stories of buildings, although it may be employed for any of the various purposes for which it is adapted.

The invention consists of a hydraulic engine, composed of a cylinder, piston, and valve, operating in a manner similar to the common steam-engine, combined with and operating a double-acting force-pump, through the direct agency of a piston-rod, to which the pistons of both are attached.

In the drawings, A represents the cylinder of the hydraulic engine, B a common slide-valve, *c c'* the ports leading to each end of the cylinder, and *d* the exhaust or escape-passage of the water employed in operating the engine; E, the piston attached to rod F, on the opposite end of which is secured the piston *E'* of the pump-cylinder *G*. The valve *B* of the engine may be operated by any suitable tripping-device, that shown being a lever or arm, *H*, weighted at the upper end, and pivoted at the lower end to the centre of the piston-rod, in such a manner as to allow the upper end of the lever to oscillate in actuating the valve.

The valve-rod *I* is supported at its end, and slides in a standard or support, *j*. At the upper ends of two other standards, *k k'*, are hinged two other levers, *l l'*, against the upper ends of which the lever *H* strikes, as it preponderates in either direction. To the valve-rod, at proper positions, are adjusted collars, *m m'*, fastened by thumb-screws, or equivalent, against which collars the lower ends of levers, *l l'*, press in actuating the valve.

N represents the supply-pipe, which conducts the water, from the fountain or other elevated source, to the pump and engine; *o* being the pipe leading to the valve-chest, and *p* a branch-pipe communicating with the two pipes *q q'*, that open into the ends of the pump-cylinder. These pipes are provided with the ordinary ball or flap-valves *r r'*, to prevent the reflux of the water.

From the pump at each end the water is forced through pipes, *s s'*, and check-valves *t t'*, into the elevating-pipe *u*, through which it is forced to the required height.

The operation of my improved machine is as follows,

The valve being at one of its extremes, as shown, the water under the pressure caused by the elevation of the fountain is forced, through port *c'*, into the end of the cylinder, where, pressing against the piston, it drives it towards the opposite end of the cylinder. As the piston *E* begins to move, it causes a corresponding movement of the pump-piston, the increased pressure of which against the water in the pump causes the valve *r* to close, while the water in *p q'* is forced by the superincumbent column, due to the common fountain, against the piston *E'* of the pump, causing the said piston to force the water in the pump through the pipe *s* and valve *f*, and up the pipe *u*, by the combined pressure of the column of water against the pistons of both pump and engine. This movement of the piston-rod carries the lever *H*, at the inclination shown, till its lower extremity comes in contact with the stuffing-box of the pump, which causes the lever to pass the vertical, and preponderate in the other direction.

The lever *H* inclining to the position shown in red lines, comes in contact with the short arm of lever *l*, the long arm of which being in contact with collar *m*, slides the rod and valve to the other extreme, closing the port *c'*. The water now being permitted to enter port *c*, starts the piston towards the other end of the cylinder, the water therein escaping through the exhaust into pipe *d*, which leads to the rooms in the lower stories, or other point where its use may be required.

This reverse movement of the pump-piston causes valve *r'* to close, when the water flowing through *q r*

presses against the piston, which is thus again driven by the conjoint action resulting from the pressure of the columns on the two pistons.

It is evident that the water would rise in pipe u to a height equal to that of the fountain, in accordance with the law of equilibrium, without the aid of the engine. It is equally obvious that whatever force is transferred from the engine to the piston of the pump, will be utilized in elevating the water in pipe u above the level of the fountain or supply.

The larger the piston of the engine, compared with that of the pump, the greater will be the height to which the water in u can be forced. If the pistons of the pump and engine are of the same size, it is evident that the water can be elevated to a height equal to twice that of the fountain above the machine, not considering the friction in the pipes and machine, which would diminish the result somewhat. By increasing the relative size of the piston of the engine, the water in pipe u may be forced proportionally higher, as experiment has fully demonstrated.

In most cities and towns, where water is supplied to the buildings by means of pipes, the source of supply is usually sufficiently elevated for the water, in seeking an equilibrium, to rise to about the middle stories, while the water that is required for the upper floors has to be carried up by hand. By the use of my improved machine, the quantity required for the upper stories can be readily elevated, without the waste other machines, occasion, as the exhaust or water discharged from the engine is conducted, by pipe d , to the various points on the lower floors and basement, where its use is required.

The pipe d being provided with a stop-cock, W , enables the operation of the machine to be controlled at pleasure, so as to pump a greater or less quantity, as required, according as the stop-cock is turned.

By closing the same, so as to prevent the escape, the machine is immediately stopped. Whenever water is drawn from pipe d , in supplying the lower floors, a proportional quantity will be elevated to the upper stories; the relative amount that will be supplied to the different floors being regulated by the relative sizes of the two pistons, which are constructed accordingly.

What I claim as my invention, is—

The engine A and pump G , connected to the supply-pipe N , by the branches o and p , so as to operate in the manner and for the purpose substantially as set forth.
